ABSTRACT: Apparatus for feeding veneer to a plywood assembly station is disclosed. The apparatus has three lift tables in line with the assembly station. The back lift table supports a supply of back veneer, the middle lift table supports a supply of face veneer, and the front lift table supports a supply of middle veneer. Two vertically stacked conveyors extend, respectively, from the outer two lift tables to lift tables to transport back veneer and face veneer, respectively, to an upper ready station. A third conveyor, below the other two conveyors, extends from the front lift table to transport middle veneer to a lower ready station. The back and face veneer are released together from the upper ready station to the assembly station, and the middle veneer is released alternately from the lower ready station to the assembly station.

APPARATUS FOR FEEDING VENEER TO PLYWOOD ASSEMBLY STATION

BACKGROUND OF THE INVENTION

The present invention relates to apparatus for feeding veneer to a plywood assembly station.

Generally, plywood is assembled manually from veneer and glued core strips, the latter of which are sandwiched between the veneer to make up the plywood sheets, or panels. Normally, four operators are used to assemble each sheet: two operators to place veneer at an assembly station, one operator to pass core strips through a gluing machine, and one operator to take the glued core strip from the gluing machine and place them on the veneer. If, for example, five-ply plywood is being assembled, the first, third and fifth ply will be veneer; the second and fourth ply will be glued core strips. It is customary to use different quality veneer for the different plies which are made of veneer, the best quality veneer being used for the face veneer. Conventionally, the veneer handlers will bring the face veneer of one sheet and the back veneer of the next sheet together in stacked relation to the assembly station, since no glued core strips are required therebetween. The middle veneer is brought alone to the assembly station.

Efforts have been made to automate the plywood assembly process, but, in general, the mechanisms developed have been quite complicated and expensive. It will be appreciated that excessive complexity or high cost of the mechanism can render the device impractical or economically infeasible.

SUMMARY OF THE INVENTION

In the present invention, simple, effective mechanism is provided for feeding veneer automatically up to an assembly station, eliminating the tiring manual transport of the veneer thereto. According to the present invention, veneer is automatically fed in coordinated relation from storage stations to ready stations adjacent the assembly station. In brief, in the preferred form of the invention, the veneer is piled on lift tables in three storage stations in line with the assembly station. The storage station for the back veneer is most remote from the assembly station; the storage station for the middle veneer is nearest the assembly station; and the storage station for the face veneer is between the other storage stations. A power-driven conveyor leads from each storage station to the plywood assembly station. The three storage stations are positioned in a line, and the conveyors extend along that line in stacked relationship, the conveyor from the back storage station (at which the back veneer is stored) on top of the conveyor from the middle storage station (at which the face veneer is stored), and the conveyor from the middle storage station on top of the conveyor from the front storage station (at which the middle veneer is stored). The terminal portion of the conveyor from the middle storage station, and the conveyor from the front storage station, define ready stations to hold veneer until needed at the assembly station. Veneer from the top conveyor drops, one sheet at a time, into the upper ready station, and falls on top of a sheet of veneer on the intermediate conveyor. Thus, at the upper ready station, two sheets of veneer, which are held in the station by a stop until required in the assembly station, comprise the face veneer on the bottom and the back veneer on top. At the lower ready station, middle veneer is held until required in the assembly station.

It is, therefore, one object of the present invention to provide conveyors for automatically carrying veneer sheets in coordinated relation to an assembly station for forming plywood sheets. It is still another object of the present invention to feed veneer, of the type and quantity required, to a plywood assembly station, and to align sheets on one edge for correct placement for introduction to the assembly station.

BRIEF DESCRIPTION OF THE DRAWINGS

FIG. 1 is a schematic diagram showing movement of the veneer by apparatus of the present invention;

FIG. 2 is a view in perspective of an assembled plywood sheet, with layers of veneer broken away to show the construction of the sheet;

FIG. 3 is a view in perspective of the feed apparatus of the present invention and the assembly station which is supplied by said apparatus;

FIG. 4 is a side view, partly in cross section, of one of the front storage station for the middle veneer;

FIG. 5 is a view taken on the line 5—5 of FIG. 4;

FIG. 6 is a view taken on the line 6—6 of FIG. 5;

FIG. 7 is a view taken on the line 7—7 of FIG. 6;

FIG. 8 is a side view, with parts broken away for clarity, of a stop to arrest the movement of veneer on a conveyor;

FIG. 9 is a side view showing the mounting on the frame of the bearing blocks for nip rollers which urge the veneer toward the assembly station;

FIG. 10 is a schematic diagram showing drive elements for the feed apparatus of the present invention;

FIG. 11 is a schematic diagram showing the location of limit switches for controlling the apparatus of the present invention;

FIG. 12 is a schematic diagram of the pneumatic circuit for the apparatus of the present invention;

FIG. 13 is a schematic diagram of the hydraulic circuit of the present invention;

FIGS. 14 to 17 inclusive are schematic electrical circuit diagrams for apparatus of the present invention; and

FIG. 18 is a schematic diagram of sequencing mechanism of the control system of the present invention.

DESCRIPTION OF THE PREFERRED EMBODIMENT

There is shown in FIGS. 1 and 3 apparatus constructed in accordance with the present invention for feeding veneer to a plywood assembly station 15. Although many features of the present invention are applicable to manufacturing three-ply plywood sheets, the invention is shown for illustrative purposes as applied to processing five-ply sheets. In a typical plywood assembly station, the veneer and glued core strips are joined together to form the plywood sheet 16 shown in FIG. 2. Each plywood sheet is made up of back, or bottom, veneer 16a, a layer of cross core strips 17, middle veneer 16b, another layer of cross core strips 17, and face, or top, veneer 16c.

The apparatus of the present invention has a support frame 14 at three veneer storage stations, two ready stations, and the conveyors therebetween. A rear, or back, storage station for the back veneer is indicated generally at 18. The rear storage station has a lift table, or elevator, 19 of the type shown in the U.S. Pat. No. 3,110,476 of W. A. Farris issued Nov. 12, 1963. A table conveyor 19a, having rollers 19b, is mounted on the lift table to receive a stack of veneer introduced into the storage station from the side, as shown in FIG. 5. The lift table 19 is raised by a hydraulic actuator 20 (FIG. 13) comprising cylinder 21 with a piston 22 therein. The piston is advanced to raise the table when motor 1MTR is energized to operate the hydraulic pump 1P. The pump 1P draws hydraulic fluid from sump SU and delivers it under pressure through line 23 to cylinder 21 behind piston 22. The table is lowered by energization of solenoid 1 SOL of hydraulic lowering valve 24 to shift the valve spool 25 thereof to the right. As spool 25 shifts to the right, port 26 of the valve, which is connected to line 23, is unblocked for communication with discharge port 27, which is connected to discharge line 28. As fluid is released through valve 24 and discharge line 28, the piston 22 retracts under the weight of the table to permit the table to lower.

A middle storage station for the face veneer, indicated generally at 35, is positioned adjacent the rear storage station and toward the assembly station therefrom. The middle storage station has a lift table, or elevator, and table conveyor which is similar to the lift table and table conveyor of the rear storage station, and which is operated in the same manner. The parts of the middle storage station lift table and controls are identified by the same numerals as the rear storage station 75 lift table and controls except that the solenoid which actuates

valve spool 25 is identified as 2 SOL and the motor which drives the pump is identified as 3MTR.

A front storage station for the middle veneer, indicated generally at 36, is positioned adjacent the middle storage station, in line with the middle and rear storage stations, but toward the assembly station therefrom. The front storage station has a lift table, or elevator, table conveyor, and controls similar to the other storage stations, which parts are identified by the same numerals as used for the other stations, except that the lowering valve solenoid is identified as 45 SOL and the motor which drives the pump is identified as 8MTR.

The lift table, or elevator, in each storage station is mounted on a stand, identified at 37 in the rear station, 38 in the middle station, and 39 in the front station. Stand 37 is higher than stand 38 which is higher than stand 39. Thus the aligned lift tables are progressively lower with the lowest table in the storage station nearest the assembly station which is aligned with the lift tables.

As shown in FIGS. 3 and 5, each storage station has an auxiliary storage conveyor, identified as 45 in the rear station, 46 in the middle station, and 47 in the front station. All of the auxiliary conveyors are of rectangular shape in plan as conveyor 47 although conveyors 45 and 46 are broken away in FIG. 3 for clarity. The height of the auxiliary storage conveyor at each storage station is equal to the height of the lift table conveyor at that station when the lift table is in its lowermost position as shown in FIG. 5. Each auxiliary storage conveyor has rotatable rollers 48' so that veneer stacked on the auxiliary conveyor of a storage station can be transferred onto the lift table conveyor of that storage station when the lift table is lowered. A stack of veneer is stored on the auxiliary conveyor of each storage station as the previous stack of veneer is being depleted in the storage station. Thus, when a stack in the storage station is depleted, the table is lowered and the stack on the auxiliary storage conveyor is immediately shifted onto the lift table so that operations can resume without delay.

Between the front storage station 36 and the assembly station, are two stacked roller conveyors, an upper conveyor 50 and a lower conveyor 51, as shown best in FIGS. 3 and 4. Each conveyor defines a ready station to hold veneer for selective release when needed in the assembly station. Each of the ready station conveyors 50, 51 have power driven rollers 52 which are turned slightly toward a side guide plate 49 to urge the veneer traveling toward the assembly station against the guide plate. Thus, sheets released from the ready stations will be properly aligned for introduction to the assembly station. The rollers 52 are driven by an endless belt 53, the upper run of which is engaged with the rollers 52 to impart rotation thereto. The belt 53 is mounted on a plurality of pulleys 48 journaled in the frame. Each ready station 50, 51 has a gate at the downstream end thereof. As shown best in FIGS. 4 and 8, the upper conveyor 50 has gate G4 pivotally mounted on axis 54 and extending between side members of the conveyor frame 14. A pneumatic actuator 55 is mounted on the frame 14 and, as shown in FIG. 12, comprises cylinder 56 with a piston 57 slidably received therein. A piston rod 58 is connected, through link 59, with gate G4 to flip the gate down to the nonblocking position, when the piston and piston rod are retracted. The actuator 55 is controlled by a valve 60 which has a solenoid operated movable valve spool member 61 therein. When the solenoid 10 SOL of the valve is deenergized, the valve spool member is in the position shown, and compressed air from a source CA is supplied through line 62 to the pressure port 63 of the valve. The air passes through the valve to motor line 64 and into cylinder 56 behind the piston 57 thereof. Thus, in this position of the valve member, the piston rod 58 is extended and the gate G4 held up to block veneer. At this time, the cylinder in front of the piston is open to the atmosphere through motor line 65, valve 60, and discharge line 66 which has restriction 67 therein. Restriction 67 limits the flow of air through line 66 to control the speed of the actuator operation. When the solenoid 10 SOL of the valve is energized, the valve member thereof is shifted to the

left of the position shown to direct compressed air entering pressure port 63 to motor line 65. In this latter position of the valve member, piston 57 and rod 58 are retracted to lower the gate and pass the veneer. Air from behind the piston escapes through line 64, valve 60 and discharge line 68 which has a restriction 69 therein to limit the speed of retraction of piston 57.

The lower ready station conveyor 51 has a similar gate, identified as G5, which is operated and controlled by an actuator 55 and valve 60 identical to the actuator and valve which controls gate G4, except that the valve member 61 is operated by a solenoid identified as 11 SOL.

As shown best in FIGS. 3, 4 and 10, the rear and middle storage stations 18 and 35 have, respectively, conveyors 75, 76 which lead from the storage stations to the upper ready station conveyor 50. The two conveyors 75, 76 lie in closely spaced stacked relation. The conveyor 75, which connects the rear storage station to the upper ready station, passes directly over the middle storage station and over the conveyor 76 which extends therefrom. Each of the conveyors 75, 76 have rollers 52 driven by an endless belt 53 mounted on pulleys 48 in the same manner as the rollers are driven in conveyors 50, 51. The rollers, as in conveyors 50, 51 are turned slightly to one side to guide the veneer against a side plate. Each conveyor 75, 76 has a gate, G2 and G3, respectively, at its downstream end. The upper conveyor 75 has, in addition, a gate G1 midway between the upstream and downstream ends of the conveyor. The gates G1, G2, and G3 are operated by the same type of actuator and valve as gates G4 and G5. Solenoids 5 SOL, 6 SOL, and 7 SOL, respectively, operate the valves 60 which control the gates G1, G2, and G3.

The endless belts 53 which drive the rollers 52 are driven as shown best in FIGS. 4 and 10. A motor 5MTR is connected by chain 81 to a sprocket 82 which is connected to the pulley 48 at the upstream end of the conveyor 75. Conveyor 75 has two endless belts 53. Drive is transmitted from the upstream belt 53 to the downstream belt 53 through a chain 88 mounted on sprockets 83, 84 which are connected, respectively, to the inner end pulleys for the belts 53. Power is transmitted by chain 91 to the sprocket 90 on the lower nip, or pinch, roller 92 which is normally engaged with, and rotates, upper pinch roll 92. A chain 95 transmits power to a sprocket 94 on brush 96 which sweeps the veneer as it emerges from the pinch rollers.

The drive system provided for the middle station conveyor 76 and the upper ready station conveyor 50 is similar to the drive system for conveyor 75. The drive motor, however, corresponding to motor 5MTR is identified as motor 7MTR.

The drive system for ready station conveyor 51 has a motor 9 9MTR which drives through chain 102 a sprocket 101 connected to the upstream end pulley 48 of the conveyor. A chain 106 engaged with sprocket 101 drives the lower nip roller 107 through sprocket 103 on the roller, and the roller in turn, drives the upper nip roller 108. A chain 109 between the lower nip roll and a sprocket 104 on brush 110 provides power for the latter. Power is transmitted from sprocket 104 on brush 110 to sprocket 105 on the lower nip roller 111 at the downstream end of conveyor 75 by chains 112 and 113 which are connected in driving relation through a double idler sprocket unit 114. The lower nip roller 111 drives the upper nip roller 112.

In each pair of nip rollers, the upper roller thereof is journaled in a bearing block 115 (see FIG. 9) which is mounted on studs 116 received in a bracket 117 secured to the conveyor frame. The studs are threaded received in the bracket and extend therethrough to receive the lower bearing block 118. Nuts 119 hold the block 118 securely to the bracket. Springs 120 mounted on the studs between the heads thereof and the upper bearing block 115 urge that block toward the bracket. Each time a sheet of veneer is received between the nip rollers, the upper nip roller (and bearing block thereof) yields (against the force of the springs) to permit the veneer to pass between the rollers. If, however, two veneer sheets inadver-

tently cling together and are introduced between the rollers, the upper roller and bearing block are raised sufficiently to operate a limit switch mounted over the upper bearing block. Limit switch 22LS is mounted at the upstream end of conveyor 75 to detect removal of two sheets of back veneer from the rear storage station; limit switch 23LS is mounted at the upstream end of conveyor 76 to detect removal of two sheets of face veneer from the middle storage station; and limit switch 35LS is mounted at the upstream end of conveyor 51 to detect removal of two middle sheets from the front storage station.

Each storage station as a carriage 129 to shift veneer, one sheet at a time, from the top of the stack on the lift table to the conveyor.

As shown best in FIGS. 5, 6 and 7 a track T1 is mounted to the frame on one side of each storage station, and a track T2 is mounted to the frame on the opposite side of each storage station. The carriage 129 has a hollow enclosed duct 130 on which is mounted a fan housing 131 containing a fan (not shown). A motor is mounted on the fan housing at each storage station to drive the fan; motor 2MTR at the rear station; motor 4MTR at the middle station; and motor 10MTR at the front station. A beam 132 is mounted on the duct, and pads 133 connected on an arm 128 extending therefrom ride in the track T1. Similar pads mounted on the bracket 134 extending from the duct ride on track T2.

The carriage 129 is advanced and retracted by a pneumatic actuator 135 having a cylinder 136 connected to the frame, as shown in FIGS. 6 and 13. The cylinder 136 has a piston 137 therein which is connected by connecting rod 138 and link 139 to beam 132. A control valve 140 has a movable valve member 141 therein. Line 62, which is connected to the source of compressed air, is connected to the pressure inlet port 142 of the valve. When the solenoid of the valve is deenergized, and the movable valve member is in the position shown, pressure is introduced through motor line 143 to the cylinder 136 in front of the piston. The cylinder behind the piston is vented to atmosphere through motor line 144, valve 140, and discharge line 145 containing a restriction 146 therein to adjust the retraction of the piston. When the valve solenoid is energized, the movable valve member 141 is shifted to the right to introduce compressed air through motor line 144 to the cylinder behind the piston to advance the piston. Air in front of the piston is vented through motor line 143, valve 140, and discharge line 147 containing restriction 148 therein to establish the speed of advance of the piston.

Each carriage duct has a bottom opening which is surrounded by skirt 160. When the fan motor is energized to drive the fan, air is evacuated from the duct to create a vacuum at the bottom opening thereof. Thus, the carriage duct defines a vacuum head which grips the top sheet of veneer on a stack on the lift table in the storage station when the table is raised to bring the top sheet into engagement with the skirt 160. Thereafter, when the control valve solenoid is energized to advance the piston 137 and connecting rod 138, the vacuum head is advanced to insert the top sheet from the stack into a funnel guide 162 (FIG. 5) at the downstream end of each of the storage stations. The funnel guide has converging top, bottom, and sides to guide a sheet between the nip rollers and iron out wrinkles in the veneer at the upstream end of conveyors 75, 76 and 51. Solenoid 3 SOL operates the solenoid valve 140 to control the rear storage station vacuum head; solenoid 4 SOL operates the solenoid valve 140 to control the middle storage station vacuum head; and solenoid 41 SOL operates the solenoid valve 140 to control the front station vacuum head.

The electrical circuit for the apparatus of the present invention is shown in FIGS. 14, 15, 16, and 17. In the schematic diagram, the switch contacts of relays are given numbers corresponding to the limit switch by which they are operated. Normally open relay contacts are indicated by vertical parallel lines; normally closed relay contacts are indicated by vertical parallel lines with a diagonal therethrough. Normally open

limit switch contacts are indicated by a weighted switch arm with the outer end below the contact point; normally closed limit switch contacts are indicated by a weighted switch arm with the outer end above the contact point. Lines which bridge drawing FIGURES are indicated by numbers L1 to L12 inclusive for convenience in following a line from one Figure to the next. Generally, there is no need to refer to these line numbers in the description which follows, and, accordingly, reference to most of these numbers is omitted in the description.

The location of the limit switches which control the operation of the feeding mechanism of the present invention is shown in FIG. 11. The limit switches 1LS, 6LS, and 12LS are located in the back, middle, and front storage station, respectively, for engagement by the top sheets on the stacks. The limit switches are operated when the stacks are raised and are not released until the last sheet is taken from the stack. The limit switches 3LS, 8LS, and 16LS are also located in the back, middle, and front storage stations, respectively, a pair (identified by like numbers) in each station, for engagement by the top veneer on the stacks when the stacks have been lifted to their proper height for feeding and for disengagement by the top veneer when the stacks are depleted to a level too low to be gripped by the vacuum heads. The switches of each pair are spaced apart to sense the level of either side of the stack. Limit switches 2LS, 7LS and 47LS are operated by the lift tables in the back, middle, and front, storage stations, respectively, when the lift tables are in their lowermost positions. Limit switch 11LS is operated by a sheet of veneer at gate G1; limit switch 17LS is operated by a sheet at gate G2; limit switch 13LS is operated by a sheet at gate G3; limit switch 20LS is operated by a sheet at gate G4; and limit switch 41LS is operated by a sheet at gate G5. Limit switch 21LS is operated by a sheet passing through gate G2.

In addition to the limit switches shown on FIG. 11, limit switch 22LS, 23LS, and 35LS are located over the bearing blocks (FIG. 9) for the nip rollers at the back storage station, the middle storage station, and the front storage station, respectively, for operation by the blocks in the event that more than one sheet at a time passes through the rollers. Limit switches 25LS, 26LS, 27LS, and 28LS are operated in sequence by cams of a timer T (FIG. 18). Photocells PC2 and PC3 are located at gates G2 and G3 to detect veneer sheets of substandard width.

The depression of pushbutton switch 4PB (FIG. 14) closes contacts 4PB1 thereof to energize relay 1C and close normally open contacts 1C1 and 1C2 thereof. With contacts 1C1 closed, relay 1C will remain energized until stop push button switch 3PB is depressed to open contacts 3PB1 thereof. When contacts 1C2 close, lines L1 and L2 are connected across source S, and the circuitry connected across those lines is ready for operation.

Assuming the back table is down and loaded with veneer, limit switch 2LS is operated to hold open normally closed contacts 2LS1 thereof. When pushbutton switch 5PB is depressed to close contacts 5PB1 thereof, relay 1CR is energized to close normally open contacts 1CR1, to close normally open contacts 1CR2, and to open normally closed contacts 1CR3. At this time, limit switch 1LS, which is operated by the presence of the top sheet of veneer when the lift table is up, is unoperated and the switch arm of contacts 1LS1 assume their normal up position, bridging contacts 1LS1a, 1LS1b. Thus, relay 1CR is sealed in through contacts 6PB2, 1LS1 and 1CR1. The two limit switches 3LS, which sense the height of the veneer stack on the back table, have normally open contacts 3LS1 and normally closed contacts 3LS2. Initially, the stack height switches 3LS are not operated, and contacts 3LS2 are closed to energize relay 1M. When relay 1M is energized, normally open contacts 1M1 are closed to energize electric motor 1MTR. The energization of motor 1MTR raises the back storage station lift table, FIG. 13, until the stack height limit switches 3LS are operated when the stack is at the proper height for feeding. During the stack elevation, limit

switch 1LS is operated to close contacts 1LS1a and 1LS1c, dropping out the coil of relay 1CR, bypassing 1CR2 contacts. At this time, relay 2M is energized through contacts 1LS1 to close contacts 2M1 and energize electric motor 2MTR which runs the fan to create a vacuum in the back vacuum head. The table continues to rise until either of the 3LS limit switches operate to deenergize motor 1MTR and stop the elevation of the stack. When the stack height limit switches 3LS are operated, contacts 3LS1 are closed and contacts 3LS2 are open. This energizes lamp 2LT to indicate the stack of back veneer is ready for feeding.

A similar circuit is provided to control the middle table which carries the face veneer. Assuming the middle table is down and loaded with veneer, limit switch 7LS is operated to hold open normally closed contacts 7LS1 thereof. When pushbutton switch 5PB is depressed to close contacts 5PB2 thereof, relay 2CR is energized to close normally open contacts 2CR1, to close normally open contacts 2CR2, and to open normally closed contacts 2CR3. At this time, limit switch 6LS, which is operated by the presence of the top sheet of veneer when the lift table is up, is unoperated and the switch arm of contacts 6LS1 assume their normal up position, bridging contacts 6LS1a, 6LS1b. Thus, relay 2CR is sealed in through contacts 7PB2, 6LS1, and 2CR1. The two limit switches 8LS, which sense the height of the veneer stack on the middle table, have normally open contacts 8LS1 and normally closed contacts 8LS2. Initially, the stack height switches 8LS are not operated, and contacts 8LS2 are closed to energize relay 3M. When relay 3M is energized, normally open contacts 3M1 are closed to energize electric motor 3MTR. The energization of motor 3MTR raises the middle storage station lift table, FIG. 13, until the stack height limit switches 8LS are operated when the stack is at the proper height for feeding. During the stack elevation, limit switch 6LS is operated to close contacts 6LS1a and 6LS1c, dropping out the coil of relay 2CR, bypassing 2CR2 contacts. At this time, relay 4M is energized to close contacts 4M1 and energize electric motor 4MTR which runs the fan to create a vacuum in the middle vacuum head. The table continues to rise until either of the 8LS limit switches operate to deenergize motor 3MTR and stop the elevation of the stack. When the stack height limit switches 8LS are operated, contacts 8LS1 are closed and contacts 8LS2 are open. This energizes lamp 3LT to indicate the stack of face veneer is ready for feeding.

A similar control circuit is associated with the front table on which the middle veneer is stacked. Assuming the front table is down and loaded with veneer, limit switch 47LS is operated to hold open normally closed contacts 47LS1 thereof. When pushbutton switch 5PB is depressed to close contacts 5PB3 thereof, relay 80CR is energized to close normally open contacts 80CR1, to close normally open contacts 80CR2 (FIG. 15), and to open normally closed contacts 80CR3. At this time, limit switch 12LS, which is operated by the presence of the top sheet of veneer when the lift table is up, is unoperated and the switch arm of contacts 12LS1 assume their normal up position, bridging contacts 12LS1a, 12LS1b. Thus, relay 80CR is sealed in through contacts 40PB2, 12LS1, and 80CR1. The two limit switches 16LS, which sense the height of the veneer stack on the back table, have normally open contacts 16LS1 and normally closed contacts 16LS2. Initially, the stack height switches 16LS are not operated, and contacts 16LS2 are closed to energize relay 8M. When relay 8M is energized, normally open contacts 8M1 are closed to energize electric motor 8MTR. The energization of motor 8MTR raises the front storage station lift table, FIG. 13, until the stack height limit switches 16LS are operated when the stack is at the proper height for feeding. During the stack elevation, limit switch 12LS is operated to close contacts 12LS1a and 12LS1c, dropping out the coil of relay 80CR, bypassing 80CR2 contacts. At this time, relay 10M is energized to close contacts 10M1 and energize electric motor 10MTR which runs the fan to create a vacuum in the front vacuum head. The table continues to rise until either of the 16LS limit switches

operate to deenergize motor 8MTR and stop the elevation of the stack. When the stack height limit switches 16LS are operated, contacts 16LS1 are closed and contacts 16LS2 are open. This energizes lamp 30LT to indicate the stack of middle veneer is ready for feeding.

At this time, then, all the stacks are up ready for feeding veneer to the assembly station. In order to prepare the system for feeding, the conveyors are next started. Push button switch 9PB is depressed, closing contacts 9PB1, 9PB2, and 9PB3 to energize, respectively, relays 5M, 7M, and 9M. Normally open contacts 5M2 close to seal in relay 5M. Normally open contacts 5M1 close when relay 5M is energized to energize the back table conveyor electric motor 5MTR; normally open contacts 7M1 close when relay 7M is energized to energize the middle table conveyor motor 7MTR; and normally open contacts 9M1 close when relay 9M is energized to energize the front table conveyor motor 9MTR (see FIG. 10). With no sheet at gate G1, limit switch 11LS is unoperated and normally closed contacts 11LS1 thereof are closed; thus, solenoid 3 SOL is energized. Solenoid 3 SOL, when energized, effects advance of the back table vacuum head (see FIG. 12) to insert a sheet of veneer into funnel guide 162 and between the nip rollers of conveyor 75, thus starting a sheet of back veneer toward the assembly station.

The switch arm of contacts 17LS1 normally bridges contacts 17LS1a and 17LS1c, and when there is no sheet at gate G2 to operate limit switch 17LS, solenoid 5 SOL is energized since normally open contacts 2M2 of relay 2M and normally closed contacts 11CR1 are closed at this time. The energization of solenoid 5 SOL effects opening of gate G1 (see FIG. 12) to permit the sheet of back veneer to pass to gate G2, which is closed at this time. With a sheet at gate G2, limit switch 17LS is operated, causing the switch arm at contacts 17LS1 to bridge contacts 17LS1a and 17LS1b. The contacts 17LS1a, 17LS1c open to deenergize solenoid 5 SOL and cause gate G1 to close.

Since there is, again, no sheet at gate G1, limit switch contacts 11LS1 close to again energize solenoid 3 SOL and feed another back sheet to conveyor 75. With the first back sheet at gate G2, gate G1 remains closed to hold the second back sheet at gate G1.

The switch arm of limit switch contacts 13LS1 normally bridges contacts 13LS1a and 13LS1c. Thus, when contacts 7M2 close on energization of relay 7M, solenoid 4 SOL is energized to actuate the middle table vacuum head feed (see FIG. 12) and shift the top sheet of face veneer to the middle table conveyor 76. When the sheet reaches gate G3, limit switch 13LS is operated, causing the switch arm at contacts 13LS to bridge contacts 13LS1a and 13LS1b. The contacts 13LS1a, 12LS1c open to deenergize solenoid 4 SOL.

When relay 9M was energized, normally open contacts 9M2 thereof closed to seal in the relay. With no sheet at gate G5 at this time, normally closed limit switch contacts 41LS1 are closed and the solenoid 41 SOL is energized to actuate the front table vacuum head feed (see FIG. 12). Thus, the top sheet of middle veneer from the front table is fed to the front table conveyor 51 and is stopped thereon by gate G5. At this time, then, there is a sheet of back veneer at gate G1; a sheet of back veneer at gate G2; a sheet of face veneer at gate G3; a sheet of middle veneer at gate G5; and no sheet at gate G4.

At this time, selector switch 1SS (FIGS. 16 and 17) is placed in the manual position (down), closing contacts 1SS1 and 1SS2 thereof. When contacts 1SS1 are closed, solenoid 6 SOL is energized through normally closed counter contacts CTR2, normally closed contacts CTR1, normally open contacts 4CR1, and normally open (now closed) contacts 20LS3, to open gate G2 (see FIG. 12), thereby passing a sheet of back veneer to gate G4. With no sheet at gate G2, limit switch contacts 17LS1a and 17LS1c (FIG. 15) again close, energizing solenoid 5 SOL to open gate G1 and pass a sheet of back veneer from gate G1 to gate G2. As the sheet arrives at gate G2, limit switch 17LS is again operated to deenergize solenoid 5 SOL and close gate G1. With no sheet at gate G1, limit

switch 11LS is released to close normally closed limit switch contacts 11LS1 and energize solenoid 3 SOL. The energization of solenoid 3 SOL actuates the back table vacuum head to introduce to the back table conveyor 75 another sheet of back veneer which stops at gate G1. Thus, now, there is a sheet of back veneer at each of the gates G1, G2, and G4; a sheet of face veneer at gate G3; and a sheet of middle veneer at gate G5.

A stepping switch ST (FIG. 17) has every other contact connected to line L1, and a relay 12CR is connected between the switch arm STA and line L2. The switch arm is actuated by energization of the coil STC of the switch ST to move from one contact to the next. Thus, when the switch arm is on every other contact, the normally open contacts 12CR1 and 12CR2 are open and the normally closed contacts 12CR3 and 12CR4 (FIG. 16) are closed. When the switch arm is on alternate contacts, the normally open contacts 12CR1 and 12CR2 are closed and the normally closed contacts 12CR3 and 12CR4 are open.

When contacts 1SS2 (FIG. 17) of selector switch 1SS close, and normally closed contacts 11CR1 are closed, the stepper coil STC will be energized if, and only if, the switch arm STA is on one of the contacts which energize relay 12CR to close the normally open contacts of the switch. If this is the case, the switch arm will be stepped to deenergize relay 12CR. If the switch arm is on a contact which does not energize relay 12CR, the stepping coil STC is not actuated. Thus, regardless of the contact on which the arm initially rested, the relay 12CR will be, or become, deenergized at this time.

At this time the selector switch 1SS is put in the automatic position (up) to close contacts 1SS3 and 1SS4 (FIG. 16) thereof. To start the automatic cycle, push button switch 25PB is depressed to energize the cycle timer motor 11MTR (see FIG. 18). The motor is connected to a gear reducer GR which has an output shaft OS on which cams CA1, CA2, CA3 and CA4 are mounted. Each cam is in registration with the actuating arm of one of the limit switches 25LS, 26LS 27LS, and 28LS. As soon as the output shaft turns, cam CA4 actuates the arm of limit switch 28LS to close the normally open contacts 28LS1 thereof (FIG. 16) and seal in the motor 11MTR for one complete cycle, at which time the contacts 28LS1 open to stop the motor 11MTR.

At the same time the motor 11MTR becomes energized, relay 7CR is picked up through normally closed contacts 8CR1 and normally closed contacts 7CR1. Relay 7CR is sealed in through the normally closed contacts 25LS1 of limit switch 25LS (FIG. 18) and normally open contacts 7CR1. At this time, then, solenoid 10 SOL is energized through normally closed contacts 12CR4 and normally closed contacts 6CR1 as normally open contacts 7CR2 close. Energization of solenoid 10 SOL opens gate G4 (FIG. 12) and releases a back sheet 16a to the plywood assembly station.

After a predetermined lapse of time, during which the men at the assembly station 15 lay a layer of glued core strips 17 on the back sheet 16a, the limit switch 27LS is operated by cam CA3 (FIG. 18). Thus, normally open contacts 27LS1 (FIG. 16) close to energize relays 8CR, 9CR and 10CR. The relays 8CR, 9CR and 10CR are sealed in through normally open contacts 9CR1 and normally closed limit switch contacts 26LS1. When relay 8CR is energized, contacts 8CR1 open to prevent premature reenergization of 7CR relay on the subsequent cycle.

After a second lapse of time while the back sheet is being fed through gate G4, the cycle timer motor 11MTR causes limit switch 25LS to be actuated. Normally closed contacts 25LS1 open to deenergize relay 7CR. Gate G4 then closes. With the absence of the back sheet at gate G4, limit switch 20LS is released to cause gate G3 to open by energizing solenoid 7 SOL and relay 14CR thru 20LS2 normally closed contacts, normally open contacts 4M2, and normally closed contacts 3CR2. When relay 3CR is energized because of a narrow sheet, solenoid 7 SOL can be energized through normally open contacts 4CR2. With the face sheet leaving gate G3,

14CR2 normally open contacts close in the circuit counter circuit CTR to register a single count toward a predetermined number of sheets of assembled plywood. Contacts 14CR1 FIG. 15 close to monitor a photo electric cell circuit, which determines if the sheet passing is of acceptable or substandard width. In the latter event, an alarm circuit is energized.

The previous face sheet leaving gate G3 arrives at gate G4 to operate limit switch 20LS, causing normally open limit switch contacts 20LS3 to close in the circuit to energize solenoid 6 SOL and cause the release of a back sheet through gate G2 onto the now placed face sheet. (From now until the predetermined count is reached in counter CTR from signals through contacts 14CR2, a pair of face and back sheets will be fed on each cycle through gate G4). As the next face sheet arrives at gate G3, through a sequence of previously described events, limit switch 13LS is actuated causing time delay relay 1TD (FIG. 15) to be energized, starting a short delay interval to close gate G2 through the opening of delay open contacts 1TD1 and the resultant deenergization of relay 4CR. Normally open 4CR1 contacts (FIG. 16) open to deenergize solenoid 6 SOL. However, if the delay interval is less than the time required for the sheet to pass gate G2, normally open limit switch 21LS1 contacts will cause solenoid 6 SOL to remain energized for the demand.

In the assembly station, the sheet fed through gate G4 continues to advance and be worked on. The cycle timer causes the limit switch 26LS to be actuated to deenergize relays 8CR, 9CR and 10CR. Also limit switch 28LS is actuated by cam CA4 to stop the cycle timer motor 11MTR.

To build a five ply sheet, alternate operation of gate 4 and gate 5 must be initiated. As previously described, the operation of selector switch 1SS prepares this operation for its proper sequence. At the conclusion of each cycle of the cycle timer motor 11MTR, limit switch 26LS is operated by cam CA2 to close normally open contacts 26LS2 (FIG. 17) and energize the stepper coil STC of stepper switch ST to move the switch arm STA thereof to the next contact, thereby energizing relay 12CR. Thus, normally open contacts 12CR1 and 12CR2 close and normally closed contacts 12CR3 and 12CR4 open. As limit switch 26LS is operated, contacts 26LS1 open to drop relays 8CR, 9CR, and 10CR (FIG. 16). When the camshaft OS driven by motor 11MTR completes one revolution, limit switch 28LS is released to open contacts 28LS1 thereof and deenergize the motor 11MTR. At this time, the circuit is conditioned for release of another sheet of veneer to the assembly station. When pushbutton switch 25PB is again pushed, the timer T (FIG. 18) initiates another cycle, and 7CR is again energized. Therefore, solenoid 11SOL (FIG. 17) is energized through normally open contacts 7CR3 and contacts 12CR2 to open gate G5 (see FIG. 12) and release a sheet of middle veneer to the assembly station. Thereafter, the operators at the assembly station lay a layer of glued core strips on the middle sheet of veneer.

As the operator's lay the glued core sheets on the sheet of middle veneer, the apparatus goes through another cycle, bringing veneer to the gates where required.

When the operators at the assembly station are ready for the face sheet (and the back sheet of the next piece of plywood which is released with the face sheet of the previous plywood piece), pushbutton 25PB is again depressed to energize the motor 11MTR, which is sealed in by the normally open contacts 28LS1 as the camshaft begins to rotate and operate limit switch 28LS. At the same time, relay 7CR is picked up and sealed in. When relay 7CR is energized, solenoid 10 SOL is energized through contacts 7CR2 of the relay to open gate G4 and release the top and bottom veneer therein.

The two stacked sheets of veneer, with the top sheet on the bottom are deposited on the glued core strips to complete one piece of plywood and provide the bottom piece for the next sheet of plywood.

When a predetermined number of sheets of plywood have been assembled (as determined by the number of sheets passing gate G3), contacts CTR1 (FIG. 17) close to energize a

signal lamp 4LT through normally open contacts 10CR1 which are closed each cycle.

The operation of limit switch 25LS by cam CA1 opens contacts 25LS1 (FIG. 16) to release relay 7CR. When normally open contacts 7CR2 of relay 7CR open, solenoid 10 SOL is deenergized to close gate G4. At the same time, normally open contacts 25LS2 (FIG. 17) close, permitting relay 11CR, to energize through now closed CTR1 and 10CR1 contacts, and be sealed in by normally open contacts 11CR2. When relay 11CR is energized, contacts 11CR3 thereof close to energize solenoid 6 SOL after normally closed contacts 20LS1 close as the pair of sheets leaves gate G4. The energization of solenoid 6 SOL opens gate G2 (FIG. 12) to deposit a sheet of back veneer at gate G4. It will be noted that solenoid 6 SOL, which operates gate G2, is held in through normally open contacts 21LS1 of limit switch 21LS. Limit switch 21LS is operated by a sheet passing through gate G2 and is released, to drop 6 SOL and close gate G2, when the sheet is completely through gate G2. As the sheet leaves gate G2, gate G1 is opened, as previously described, to feed another sheet to gate G2. A new sheet is then supplied to gate G1 as previously described. As relay 11CR is energized, normally open contacts 11CR4 thereof close to energize a signal AB3, through normally open contacts 10CR3, to indicate that the desired count has been reached. Normally closed contacts 10CR4 prevent the alarm from being sounded before relay 11CR is energized.

When the supply of veneer on the back table is depleted, pushbutton switch 6PB (FIG. 14) is depressed, closing contacts 6PB1 and opening contacts 6PB2. Opening of contacts 6PB2 disables relays 1CR, 1M, 2M, and lamp 2LT. The closing of contacts 6PB1 energizes solenoid 1 SOL through normally closed contacts 1CR3 and 2LS1. The energization of solenoid 1 SOL lowers the back lift table (see FIG. 13). Contacts 2LS1 will remain closed until the table operates limit switch 2LS as it reaches the lower limit of its travel, at which time contacts 2LS1 open to drop solenoid 1 SOL. Similarly, when the middle table is empty, operation of pushbutton switch 7PB will close contacts 7PB1 and open contacts 7PB2 thereof. Opening contacts 7PB2 will disable relays 2CR, 3M, 4M, and lamp 3LT. Closing contacts 7PB1 will energize solenoid 2SOL through normally closed contacts 2CR3 and normally closed contacts 7LS1. The energization of solenoid 2SOL lowers the middle lift table (see FIG. 13). Contacts 7LS1 will remain closed until the table operates limit switch 7LS as it reaches the lower limit of travel, at which time contacts 7LS1 open to drop solenoid 2SOL. In a like manner, when the front lift table is empty, push button switch 40PB is depressed to close contacts 40PB1 and open contacts 40PB2. Opening contacts 40PB2 disables relays 80CR, 8M, 10M, and lamp 30LT. The closing of contacts 40PB1 energizes solenoid 45 SOL through normally closed contacts 80CR3 and normally closed contacts 47LS1. The energization of solenoid 45 SOL lowers the front lift table (FIG. 13). Contacts 47LS1 will remain closed until the table operates limit switch 47LS as it reaches the lower limit of its travel, at which time contacts 47LS1 will open to drop solenoid 45 SOL.

Two detector circuits 1SW and 2SW are connected across lines L1, L2 to produce a warning signal when a sheet of sub-standard width is at gate G2 or gate G3. When photocell PC2 or PC3, which are positioned at the edge of a sheet of normal width at gates G2 and G3, respectively, is not operated by a sheet at those gates because the sheet is not wide enough to shield the photocell lens from the light, normally open contacts 1SW1 or normally open contacts 2SW1 close, depending on whether the narrow sheet is at gate G2 or gate G3. Relay 14CR is energized to close normally open contacts 14CR1 the same time solenoid 7 SOL is energized to open gate G3. Therefore, whenever a narrow sheet passes through gate G3, relays 3CR and 5CR are energized. When relay 3CR is energized, normally open contacts 3CR1 thereof (FIG. 17) close and, since normally open contacts 14CR3 are closed at the same time, alarm bell AB1 rings. The energization of relay 5CR

opens normally closed contacts 5CR1 (FIG. 17) to disable the counter CTR and prevent registration of a count as the narrow sheet passes through gate G3. When a sheet is at gate G2, the switch arm of contacts 17LS is raised to bridge contacts 17LS1a and 17LS1c (FIG. 15). Relay 13CR (FIG. 16) is energized to close normally open contacts 13CR1 the same time solenoid 6 SOL is energized to open gate G2. Therefore, whenever a narrow sheet passes through gate G2, relay 6CR is energized. When relay 6CR is energized to close normally open contacts 6CR1 (FIG. 17), alarm bell AB2 is energized since normally open contacts 13CR2 are closed at the time. Alarm bells AB1 and AB2, when energized, are sealed in through contacts 3CR1 and 6CR1, respectively, and contacts 30PB1 of alarm reset pushbutton 30PB. When pushbutton 30PB is depressed to release alarm bells AB1, AB2, solenoid 6 SOL is momentarily energized, when there is a narrow sheet at gate G4, to open gate G2 and replace the narrow sheet which is removed by the operator.

When more than one sheet of veneer is introduced inadvertently by the back, middle, or front vacuum head to the nip rollers, limit switch 22LS, 23LS, or 35LS will be operated, to close either normally open contacts 22LS1, 23LS1, or 35LS1 (FIG. 16). When any of these contacts close, the alarm horn AH is connected across lines L1, L2 to sound an alarm.

Pushbutton switch 49PB, having two normally closed contacts 49PB1 (FIG. 16), 49PB2 (FIG. 17), and normally open contacts 49PB3, 49PB4 is provided to reset the counter CTR.

In the operation of the apparatus of the present invention, veneer is fed alternately from the upper ready station 50 and the lower ready station 51 to the plywood assembly station 15: the veneer from the upper ready station comprising a face sheet 16c and a back sheet 16a released as a unit with the face sheet on the bottom, and the veneer from the lower ready station comprising a single sheet of middle veneer 16b.

Sheets of veneer are supplied alternately from the back, or rear, station conveyor 75 and from the middle station conveyor 76 to the upper ready station. Veneer from the front storage station is fed directly to the lower ready station 51.

Sheets of veneer are fed from the storage stations 18, 35, and 36 to the conveyors and ready station by a movable vacuum head 129.

The control of the series of gates G1, G2, G3, G4, and G5, and the control of the vacuum heads in the storage stations, coordinates the flow of veneer from the storage stations to the assembly station. Sheets are automatically moved downstream, from gate to gate, as required, for ultimate release to the assembly station. The assembly station may be similar to the assembly station shown and described in the copending patent application of Billett and Viitanen entitled APPARATUS FOR ASSEMBLING VENEER INTO PLYWOOD SHEETS filed Apr. 1, 1969, Ser. No. 813,812, and assigned to the same assignee as the present invention.

Although the best mode contemplated for carrying out the present invention has been herein shown and described, it will be apparent that modification and variation may be made without departing from what is regarded to be the subject matter of the invention.

I claim:

1. In a machine to assemble plywood veneer in an assembly station to form a plywood sheet, the combination comprising a first storage station for back veneer, a second storage station for face veneer, and a third storage station for middle veneer, a first ready station for face and back veneer, a second ready station for middle veneer, means to transfer back veneer from said first storage station to said first ready station, means to transfer face veneer from said second storage station to said first ready station, means to transfer middle veneer from said third storage station to said second ready station, and means to transfer veneer from said ready stations to said assembly station.

2. The machine of claim 1 including means selectively to control the transfer of veneer from said ready stations to feed the veneer alternately from said first ready station and from said second ready station.

3. The machine of claim 1 in which said first and second ready stations are positioned in stacked relationship.

4. The machine of claim 3 in which said means to transfer veneer to said first ready station constitutes stacked conveyors leading, respectively, from said first storage station and said second storage station.

5. The apparatus of claim 1 in which said storage stations are aligned with the assembly station and in which said first storage station is most remote from the assembly station and said third storage station is closest to the assembly station.

6. The apparatus of claim 5 in which said ready stations are in stacked relation with said first ready station on top of said second ready station.

7. In a machine to assemble plywood veneer in an assembly station to form a plywood sheet, the combination comprising a plurality of storage stations for veneer of different quality, said storage stations aligned with said assembly station, a plurality of conveyors to receive veneer from said storage stations, said conveyors arrayed in stacked relation and extending respectively from said storage stations toward said assembly station, a plurality of ready stations, said ready stations mounted in stacked relation adjacent the assembly station and each ready station positioned to receive veneer from a particular conveyor, at least one of said ready stations positioned to receive

veneer from more than one of said conveyors, means to control the flow of veneer from each storage station to each ready station, and means to control the release of veneer from the ready stations to the assembly station.

5 8. In a machine to assemble plywood veneer in an assembly station to form a plywood sheet, the combination comprising a first storage station for back veneer, a second storage station for face veneer, and a third storage station for middle veneer, a plurality of ready stations to receive the veneer, means to

10 transfer back veneer from said first storage station to one of said ready stations, means to transfer face veneer from said second storage station to one of said ready stations, means to transfer middle veneer from said third storage station to one of said ready stations, and means to release the face and back

15 veneer substantially simultaneously to the assembly station and to release the middle veneer sequentially to said substantially simultaneous release of the face and back veneer.

9. In plywood layup apparatus having an assembly station, the combination comprising, a plurality of storage stations for

20 plywood veneer, power driven conveyors extending between said storage stations and said assembly station to deliver the veneer to the assembly station, and an auxiliary storage station adjacent each of said storage stations.

UNITED STATES PATENT OFFICE
CERTIFICATE OF CORRECTION

Patent No. 3,603,463 Dated September 7, 1971

Inventor(s) RONALD J. BILLETT, DONALD W. CHAMBERLIN, and
ARTHUR L. MCGEE

It is certified that error appears in the above-identified patent
and that said Letters Patent are hereby corrected as shown below:

Abstract, line 7, delete "to lift tables"

Col. 1, line 65, after "provide" insert -- simple, effective,
mechanism for moving plywood veneer to a
plywood assembly station. It is another
object of the present invention to provide --

Col. 5, line 72, after "corresponding" insert -- to the relays
by which they are actuated, and limit switch con-
tacts are given numbers corresponding --

Col. 8, line 52, change "12LS1c" to -- 13LS1c --

Col. 8, line 54, delete (first occurrence) "no"

Signed and sealed this 6th day of June 1972.
